UNITED STATES PATENT OFFICE.

JOHN JOHNSON, OF DUPONT, INDIANA.

RAILWAY-SWITCH FROG.

1,191,314.

Specification of Letters Patent. Patented July 18, 1916.

Application filed January 24, 1916. Serial No. 73,931.

To all whom it may concern:

Be it known that I, JOHN JOHNSON, a citizen of the United States, residing at Du-
pont, in the county of Jefferson and State
of Indiana, have invented certain new and
useful Improvements in Railway-Switch
Frogs, of which the following is a specifica-
tion, reference being had to the accompa-
nying drawings.

10 This invention relates to an improved
railway switch frog and has for its primary
object to provide a device of this character
consisting of a single integral casting which
may be readily arranged in place in the
15 track and connected to the track and switch
rails.

The invention has for another important
object to provide a switch frog which is of
such construction that the spikes for fasten-
20 ing the frog to the rail ties have their heads
disposed contiguous to the body of the frog
at its base so that the frog is more securely
and rigidly held in place.

25 It is a further general object of the in-
vention to provide a cast metal railway
switch frog which may be inexpensively
produced, is of great stability, and requires
but little care or attention after it is ar-
ranged in place.

30 With the above and other objects in view,
my invention consists in the novel features
of construction, combination and arrange-
ment of parts to be hereinafter more fully
described, claimed and illustrated in the ac-
35 companying drawing, in which,

Figure 1 is a top plan view showing my
improved railway frog arranged in position
and connected to the track and the switch
rails; Fig. 2 is a perspective view of the
40 frog.

Referring in detail to the drawing, 5
designates the main rails and 6 the switch
rails. The improved frog forming the sub-
ject-matter of the present application, is
45 constructed from a single integral casting
generally designated by the numeral 7. The body of this casting includes two longi-
tudinally tapering portions 8 which are in-
tegral with each other at the approximate
50 longitudinal center of the frog body, which
is the point of minimum cross-sectional
area. From this point to the opposite ends
of the frog, the same gradually increases in
55 area. One of the portions 8 is provided with
a continuous head indicated at 9, produced
by forming the relatively narrow longitudi-

nal flanges 10 on opposite sides of the taper-
ing body section. At the center of the frog,
the head 9 tapers to a point, as indicated at
11. At the end of the head 9, the frog body 60
is formed with a vertical channel or groove
indicated at 12, to accommodate the fish
plates or angle bars 13 which connect one of
the main track rails 5 and one of the switch
rails 6 in proper alinement with the flanges 65
10 on the head of the frog. The other body
portion 8 of the frog is formed on its upper
surface with the two converging heads 14,
the top surface of the frog between these
heads being in a lower horizontal plane. 70
These heads also provide flanges 15 on the
opposite sides of the frog body. The inner
edges of these heads 14, at their inner ends,
are extended in spaced parallel relation to
the point of the head 11, thereby providing 75
the channels or grooves 16 for the wheel
flanges. It will be understood, of course,
that the other sections of the main track
rail 5 and switch rail 6 are connected to this
latter end of the frog which is vertically 80
cut away or channeled, as at 17, between the
spaced heads 14, in the same manner as here-
tofore described.

The body of the frog is provided upon op-
posite sides and at its base with the nar-
row longitudinally extending flanges 18. 85
By making these flanges quite narrow, the
heads of the fastening spikes which secure
the frog to the ties will be disposed as close
as possible to the body of the frog, thus 90
affording greater security.

From the foregoing description, taken in
connection with the accompanying draw-
ing, the construction, manner of use and
several advantages of the invention will be 95
fully and clearly understood.

My improved railway frog, though ex-
ceedingly simple in its construction, is,
nevertheless, highly advantageous in prac-
tical use, as it obviates the necessity of giv- 100
ing the switch rail connections frequent ex-
amination. It is apparent, of course, that
while I have above referred to a particular
manner of connecting the switch and track
rails to the frog, various other means may 105
be employed for this purpose. By construct-
ing the frog in one integral casting, the
necessity of employing bolts or other connec-
tions is entirely dispensed with, thus greatly
lessening the cost of installation and, at the 110
same time, producing a structure which is
of greater durability.

While I have shown and described the preferred construction and arrangement of the several features of the device, it will be understood that the same is susceptible of considerable modification and I, therefore, reserve the privilege of adopting all such legitimate modifications therein as may be fairly embodied within the spirit and scope of the invention as claimed.

Having thus fully described my invention, what I desire to claim and secure by Letters Patent is:—

1. The herein described switch frog consisting of a single integral casting having a body portion gradually decreasing in thickness from each end of the frog to its center, one of the end portions of the frog body having a head formed thereon of uniformly greater width than the thickness of said end portion, said head at its inner end terminating in a point projecting beyond the longitudinal center of the frog, and spaced inwardly converging heads formed on the upper surface of the other end portion of the frog body at its opposite edges and projecting beyond the side faces thereof to form flanges, the inner opposed edges of said latter heads at their inner ends being obliquely inclined and extended beyond the terminal of said first named head and in

parallel relation to the opposite sides thereof and terminating at the approximate center of the frog.

2. The herein described switch frog consisting of a single solid metal casting gradually decreasing in cross-sectional area from its opposite ends to its center and provided upon the upper surface of one of said end portions with a head of greater width than the thickness of the body of the frog and projecting beyond the side faces thereof to provide longitudinal flanges, said head tapering to a point at the center of the frog, and spaced inwardly converging heads formed upon the upper surface of the frog at its other end and having their inner edges extended in spaced parallel relation to the point of the first named head, said latter converging heads also projecting beyond the opposite side faces of the frog to provide longitudinal flanges thereon and a narrow longitudinally extending flange formed upon each side of the frog body at its base.

In testimony whereof I hereunto affix my signature in the presence of two witnesses.

JOHN JOHNSON.

Witnesses:

FRED TURNER,
IRA McNUTT.
